UNITED STATES PATENT OFFICE.

FRANCIS H. BROWN AND OTTO REESER, OF PHILADELPHIA, PENNSYLVANIA, ASSIGNEES, BY DIRECT AND MESNE ASSIGNMENTS, OF ONE-FOURTH TO JOHN S. LATTA, ONE-FOURTH TO THOMAS L. LATTA, ONE-FOURTH TO JAMES LATTA, AND ONE-FOURTH TO SAID FRANCIS H. BROWN, ALL OF PHILADELPHIA, PENNSYLVANIA.

REGULATING AND CONTROLLING DEVICE.

1,247,217.

Specification of Letters Patent.

Patented Nov. 20, 1917.

Application filed September 22, 1910, Serial No. 583,176. Renewed April 18, 1917. Serial No. 163,036.

To all whom it may concern:

Be it known that we, FRANCIS H. BROWN and OTTO REESER, both citizens of the United States, residing in the city and county of Philadelphia, State of Pennsylvania, have invented a new and useful Regulating and Controlling Device, of which the following is a specification.

Our invention consists of a novel construction of regulating and controlling device wherein a novel type of diaphragm is employed which is operatively connected to other mechanism in a novel manner in order to actuate the same or to be actuated thereby. It further consists of a novel regulating and controlling device, wherein a motor is controlled in a novel manner by means of a regulator, said motor being adapted to control in a novel manner, a valve connection.

It further consists of a novel manner of and construction for connecting the different parts in operative relation with respect to each other.

It further consists of other novel features of construction, all as will be herein-after fully set forth.

For the purpose of illustrating our invention, we have shown in the drawings an embodiment thereof which is at present preferred by us, since the same will give in practice satisfactory and reliable results, although it is to be understood that the various instrumentalities of which our invention consists can be variously arranged and organized and that our invention is not limited to the precise arrangement and organization of these instrumentalities as herein shown and described.

Figure 1 represents a sectional elevation of our invention, showing the same operatively connected to a motor.

Fig. 2 represents a sectional elevation of the controlling device seen in Fig. 1, but showing the other side of this device and the controlling valve which is actuated by the motor seen in Fig. 1.

Fig. 3 represents a side elevation of a portion of Fig. 1.

Fig. 4 represents a side elevation of a portion of Fig. 3.

Fig. 5 represents a section on line x—x, Fig. 3.

Fig. 6 represents a plan view of a portion of Fig. 2.

Fig. 7 represents a sectional plan view of a portion of Fig. 2.

Fig. 8 represents a side elevation of a portion of the valve seen in Fig. 2.

Fig. 9 represents a plan view of Figs. 1 and 2.

Fig. 10 represents a section on line z—z, Fig. 9.

Fig. 11 represents a sectional view on line y—y, Fig. 9.

Fig. 12 represents a sectional elevation of the piston and valve bushing which is also seen in Fig. 1.

Fig. 13 represents a sectional elevation showing more clearly the valve bushing and parts, and a portion of the valves.

Fig. 14 represents a top plan view of Fig. 12.

Similar numerals of reference indicate corresponding parts in the figures.

Referring now more particularly to Figs. 1 to 6 inclusive, we have shown in these figures our novel regulating and controlling device as being employed to control in a novel manner, a novel motor and valve mechanism.

Referring first more particularly to Figs. 1 and 2, it will be seen that our novel type of regulating device is adapted to actuate a lever 56 exterior of the casing, and in this embodiment the casing is formed of the members 43 and 44 and a conduit 45 is provided leading to the chamber 46 on one side of the diaphragm.

47 designates a valve controlled conduit leading from the chamber 46 and discharging into the chamber 48 on the opposite side of the diaphragm, which latter is provided with suitable drainage means. 49 designates a float mounted within the chamber 47 and forming a cushion, as will be herein-after more particularly described.

Referring now more particularly to Figs.

9, 10, and 11, it will be noticed that the block 18 is provided with a laterally extending aperture 50 in which is located a lever 51 suitably fulcrumed at 52 and 53, as seen in Fig. 9.

54 designates a lever, one end of which is secured to the lever 51, the other end thereof being fulcrumed at 55, it being understood that the block 18, rings 19 and spacing washer 17, are suitably apertured at this point in order to permit the free movement of the lever 54.

56 designates a lever having one end connected with the lever 51, the other end thereof of extending exterior of the casing 43 and having secured thereto an elbow lever 57, it being understood that the block 18, rings 19, and spacing washer 17 are suitably apertured to permit the rocking movement of the lever 56.

58 designates a bell crank lever fulcrumed at 59 and having one arm provided with a bracket 60 with which is adapted to co-act an adjusting screw 61, the latter also co-acting with the bracket 62 carried by one end of the arm 57 secured to the lever 56.

Referring now more particularly to Fig. 11, 63 designates a limiting member which, in the present instance, consists of a screw 30 or pin having threaded engagement with the spacing washer 17 and having its inner ends provided with heads of different diameters, as indicated at 64, 65, 66, 67 and 68, it being understood that these heads are located in a recess which extends through the rings 19 and also into the block 18, the purpose of the graduations 64, 65, 66, 67 and 68 on the pin 63 is to permit the spacing member 18 to freely move in unison with the flexible members 15 and 16 of the diaphragm, it being seen that the ring nearest to the washer 17 has the least amount of movement, while the ring nearest to the block 18 is capable of the greatest amount of relative movement.

The arm of the bell crank lever 58 which carries the crank 60 is provided with an adjustable counterweight 69 which takes up any lost motion between the parts. The opposite end of the bell crank lever 58 has pivoted thereto at 70 a bracket 71 having arms 72 which carry a rod 73 which is adapted to be engaged by the fork 74 carried by one end of a bell crank lever 75 fulcrumed at 76 in a bracket 77, which latter is secured to the hollow shaft 78 of a piston 79 located in a casing 80 suitably carried by the extension 81 of the lower casing member of the device.

In order to accurately control the amount 60 of movement of the piston 79 relatively to the variation in fluid pressure on the diaphragm, we provide the lower end of the lever 71 with the gear teeth 171 which co-act with the manually controlled worm 172.

82 designates a rod carried by the bracket

77 and adapted to travel in an aperture 83 to prevent rotation of the bracket 77 during its reciprocations. One end of the bell crank lever 75 has pivoted thereto one end of a link 84, the other end of which is pivoted to 70 the valve stem 85, the latter passing through the bracket 77 and provided with a suitable packing nut 86 carried by said bracket, said valve stem 85 also passing through the motor or piston shaft 78, which is adapted to 75 reciprocate in the casing 80, which latter is provided with a suitable fluid inlet 87.

In order that the operation of the motor may be readily understood, we will now describe the manner in which the fluid passes 80 to operate the motor.

The piston 79 is provided with a reduced diameter 88, thereby forming a chamber which is always filled with the motive fluid which passes through the inlet ports 89 to 85 the chamber formed by the heads 90 and 91 on the valve casing 92 which is fixed in the bore 93 of the piston 79.

94 designates the inlet in the motor casing which is always open to the motive fluid supply, so that when the valve heads 95 and 96 are in the position seen in Fig. 13, the motive fluid will be prevented from operating the piston.

Assuming that the valve stem 85 moves 95 downwardly, then the motive fluid may pass through the port 95 around the reduced neck 97 of the valve, thence through the port 98 and through the passages 99 in rear of the piston 79, and causes the latter to move 100 downwardly, the motive fluid within the motor being permitted to escape through the passages 100, thence through ports 101 and through the end of the valve casing 92, thence through the motor shaft 78 and 105 through the passage 102 in the bracket 103, with which communicates a conduit 104 leading to a suitable point of discharge.

Assuming that the valve stem 85 is moved upwardly, then the motive fluid will enter 110 through the inlet 94, passing around the neck 97 of the valve, thence through the port 105 through passages 100 beneath the piston 79 to cause the piston to move upwardly, thereby carrying with it the 115 bracket 77.

As the piston 79 moves upwardly the fluid in rear of the piston may escape through the passages 99, the ports 106, through the end of the valve bushing 92 and thence through 120 port 107, passage 108 and port 109 to the hollow motor shaft 78, and thence through the passage 102 and through the conduit 104.

The bracket 103 has mounted therein a pin or stud 110 which is adapted to co-act with the forked end of a lever 111 which is fulcrumed at 112 in an arm carried by the lower casing member of the device. The opposite end of said lever 111 is suitably forked and adapted to engage a pin 113 car- 125 130

ried by a valve stem 114 which is connected with a cup-shaped valve 115 mounted in a casing 116 carried by the flange 81 of the casing 44, whereby the valve 115 is capable of both a reciprocating and a rotary motion.

The valve casing 116 is provided with an inlet 117 which communicates with an annular passage 118 provided with a plurality of ports 119 communicating with the valve chamber 120. The valve 115 is provided with ports 121 which are adapted to register at certain times with the ports 119 as will later be more fully described, so that the fluid may pass through the port 117, thence into the chamber 118, through the ports 119 and ports 121 into a chamber 120 and thence through the outlet 122.

The novel type of mechanism which we have just described is adapted to receive not only a reciprocating movement but the rotation thereof is controlled in a novel manner which we will now describe.

The upper end of the valve stem 114 has secured thereto a bracket 123 carrying a pin 24 which is mounted in a recessed block 125, the block 125 having passing therethrough a rod 126, the lower end of which is carried by an arm 127 secured to a lever 128 which is fulcrumed at 129 to an arm 130, carried by a bracket 131 adapted to be secured to a casing 116.

132 designates a worm mounted in the bracket 131 adapted to co-act with the teeth 133 on the lower end of the arm 128, whereby said arm may be angularly inclined in order to cause any desired rotation of the valve stem 114, and thereby control the amount of opening of the ports 121 and 119.

The operation of my invention will now be readily apparent and is as follows:-

Referring to the construction seen in Figs. 1 to 6 inclusive, we have shown a construction wherein the movement of the diaphragm is communicated exteriorly of the casing, and in this construction the fluid enters the conduit 45, and assuming that the valve in the pipe 47 is open, the fluid may pass into the chamber 48, so that the pressure in the chambers 46 and 48 on opposite sides of the diaphragm will be equalized, it being understood that an air cushion is formed in the bell float 49 or its equivalent.

The valve in the pipe 47 will now be closed, so that a desired or predetermined pressure will be maintained in the chamber 48 and variable pressure will be maintained in the chamber 46, since the conduit 45 will be connected with a source of supply which is constantly varying.

Assuming now that the pressure in the chamber 46 increases, it will be apparent that that diaphragm will move downwardly and owing to the manner in which the levers 54, 51 and 56 are mounted in the diaphragm, they will move downwardly in

unison therewith, so that a downward pull will be imparted to the bell crank lever 58, thereby causing the upper end thereof to move downwardly, whereupon the bracket 71 will be moved outwardly, so that the bell crank lever 75 will be actuated and cause the valve stem 85 to move downwardly.

When the valve stem 85 moves downwardly, motive fluid may enter through the port 87, thence to the ports 89 and 94 through the port 98, as best understood by reference to Figs. 15 and 16, through the passages 99 above the piston 79, and cause the piston 79 to move downwardly, thereby causing the bracket 103 to move downwardly. As the bracket 103 is moved downwardly, the lever 111 will be rocked on its fulcrum 112, thereby causing the valve stem 114 to be raised, and owing to the manner in which the upper end of the valve stem 114 acts with the lever 126, it will be apparent, that in unison with the reciprocating of the valve stem 114, that the valve 115 carried thereby will be rotated, thereby causing the valve 115 to open and permit fluid to pass through the port 117, through the ports 121 and 124, and thence through the discharge port 122 to a desired point of utilization. The amount of rotation imparted to the valve 115 is regulated as desired by manipulating the worm 133, whereby the angle which the lever 126 assumes with respect to the longitudinal axis of the valve stem 114 may be varied as desired. The amount of movement imparted to the piston 79 may be controlled as desired by manipulating the worm 172, which as will be apparent, varies the throw of the valve stem 85.

Owing to the provision of the novel means for regulating the throw of the valve, the movement of the piston 70 may be accurately regulated, so that any desired movement of the piston may be produced for a predetermined variation in pressure in the chamber 46 on one side of the diaphragm.

When the diaphragm moves upwardly, it will be apparent that the motor will be actuated in a reverse direction, thereby causing reverse action to that above described of the valve 115 and its adjuncts.

It will be apparent that when the worm 172 is actuated, the lever 71 will move on its pivot so that the amount of movement imparted to the piston 79 may be varied as desired, it being apparent that we employ a somewhat similar construction, as seen in Fig. 2, for varying the amount of rotary movement imparted to the valve 115.

It will be apparent that the novel construction of diaphragm herein disclosed forms an extended flexible joint which enables the same to be employed in connection with much higher pressures than has heretofore been deemed possible, and it has been found in actual practice that owing to the

5 formation of this extended flexible joint a
without injury to the diaphragm or destroy-
ing in any manner the sensibility of the
flexible member.

10 In so far as we are aware, we are the
first to provide means for varying the stroke
of the valve to vary the length of stroke of
the piston either alone or in combination
with a controlling valve, the action of which
depends upon the length of stroke of the
piston.

15 It will be apparent that in accordance
with the present invention, novel means are
provided whereby a motor controlled by a
pressure or other regulator will be employed
to automatically control a valve. Attention
20 is also directed to the novel means employed
for controlling the passage of the steam or
other motive fluid and for controlling the
amount of movement imparted to such
means.

25 It will now be apparent that we have de-
vised a novel and useful construction of a
regulating and controlling device which em-
bodies the features of advantage enumerated
as desirable in the statement of the inven-
30 tion and the above description, and while we
have, in the present instance, shown and de-
scribed a preferred embodiment thereof
which has been found in practice to give sat-
isfactory and reliable results, it is to be un-
35 derstood that the same is susceptible of
modification in various particulars without
departing from the spirit or scope of the
invention or sacrificing any of its advan-
tages.

40 Having thus described our invention, what
we claim as new and desire to secure by Let-
ters Patent, is:—

1. In a device of the character stated, a
45 valve casing having an inlet and an outlet,
a valve controlling said inlet and outlet and
mounted to reciprocate and rotate in said
casing, a motor to reciprocate said valve,
means to automatically effect the rotation of
50 said valve during its reciprocation, and a
pressure regulator controlling said motor.

2. In a device of the character stated, a
casing having an inlet and an outlet, a
55 valve mounted to reciprocate and rotate
in said casing and to control said inlet and
outlet, a motor operatively connected to said
valve, means to automatically effect the ro-
tation of said valve during its reciprocation,
60 a pressure regulator controlling said motor,
and means to vary the amount of rotation of
said valve during the reciprocating move-
ment thereof.

3. In a device of the character stated, a
casing having an inlet and an outlet, a
65 valve within said casing to control said
inlet and outlet, a motor operatively con-

nected with said valve to reciprocate the
same, means to impart a rotary movement
to said valve during its reciprocation, and
means to automatically control said motor.

4. In a device of the character stated, a
70 casing having an inlet and an outlet, a
valve mounted to reciprocate and rotate
therein and to control said inlet and outlet,
a valve stem, a motor, a lever suitably ful-
crumed and having one end actuated by said
75 motor and the other end operatively con-
nected with said valve stem to reciprocate
the latter and permit the partial rotation
thereof, means to actuate said motor, and
means to impart a rotary movement to said
80 valve during its reciprocation.

5. In a device of the character stated, a
casing having an inlet and an outlet, a
85 valve controlling said inlet and outlet
and mounted to rotate and reciprocate in
said casing, a stem for said valve, a pin on
said stem, a lever having a forked end en-
gaging said pin, a motor to actuate said
90 lever, a valve controlling said motor, means
controlled by a variable fluid pressure to con-
trol the valve of said motor, and means to
impart a rotary movement to said valve
during its reciprocation.

6. In a device of the character stated, a
95 casing having an inlet and an outlet, a
valve mounted to reciprocate and rotate
in said casing and to control said inlet and
said outlet, a motor to reciprocate said valve,
a pressure regulator to control the opera-
100 tion of said motor, a member operatively
connected with said valve, a rod in sliding
engagement with said member, and means
to angularly displace said rod to vary the
amount of rotation imparted to said valve.

7. In a device of the character stated, a
105 casing having an inlet and an outlet, a
valve mounted to reciprocate and rotate
therein and to control said inlet and out-
let, a stem for said valve, a bracket on said
stem, a block in operative engagement with
110 said bracket, a rod in sliding engagement
with said block, and inclined at an angle to
the longitudinal axis of said valve stem,
whereby said valve will partially rotate dur-
ing its reciprocating movement, a motor to
115 reciprocate said valve, and a pressure regu-
lator to automatically control the operation
of said motor.

8. In a device of the character stated, a
120 casing having an inlet and an outlet, a
valve mounted to reciprocate and rotate in
said casing, and to control said inlet and
outlet, a stem for said valve, a bracket ad-
justably mounted on said stem, a block con-
125 nected with said bracket, a rod in sliding
engagement with said block, means to angu-
larly adjust said rod, a motor to reciprocate
said valve, and a pressure regulator to auto-
matically control said motor.

9. In a device of the character stated, a
130

casing having an inlet and an outlet, a valve mounted to reciprocate and rotate in said casing and to control said inlet and outlet, a stem for said valve, a bracket carried by said stem, a pin carried by said bracket, a block having a recess into which said pin extends, a rod in sliding engagement with said block, an arm carried by said rod, a lever movably mounted and connected with said arm, means to move said

lever to vary the angularity of said rod with respect to said valve stem, a motor to reciprocate said valve, and means to automatically control said motor.
